METALLIC LEAF APPLYING ATTACHMENT FOR PRINTING PRESSES

Filed May 3, 1924

2 Sheets-Sheet 2

Inventor
James C. Coon.
By his Attorney
Herbert H. Thompson

UNITED STATES PATENT OFFICE.

JAMES C. COON, OF BROOKLYN, NEW YORK.

METALLIC-LEAF-APPLYING ATTACHMENT FOR PRINTING PRESSES.

Application filed May 3, 1924. Serial No. 710,714.

To all whom it may concern:

Be it known that I, JAMES C. COON, a citizen of the United States of America, residing at Brooklyn, in the county of Kings 5 and State of New York, have invented certain new and useful Improvements in Metallic-Leaf-Applying Attachments for Printing Presses, of which the following is a specification.

10 This invention relates to the art of applying gold, silver, or aluminum leaf, or the like, to a paper or other surface. While many special machines have been devised for this purpose, such machines are expensive 15 and are usually adapted for no other purpose. For purposes of illustration, I have selected a press in which both the platen and bed oscillate, but it will be obvious that my invention is equally applicable to other 20 types of presses, such as those in which only the platen oscillates.

One object of my invention is to devise 25 an attachment for ordinary small printing presses which will apply the leaf automatically to a sheet of paper or the like during the running of the press in the same manner as when run for printing. My attachment may be manufactured as a separate 30 article of manufacture, easily placed on the press and removed when a job is finished.

A further object of the invention is to 35 improve metallic leaf applying machines by rendering them more completely automatic in character, so that fancy labels and the like may be leaf printed (or embossed) with great rapidity. Other objects of my invention will appear as the description proceeds.

Referring to the drawings in which what 40 I now consider the preferred form of my invention is shown—

Fig. 1 is a side elevation of a standard job printing press with my attachment mounted thereon.

45 Fig. 2 is an enlarged detail of the pawl and ratchet feeding mechanism for the strips.

Fig. 3 is a cross section of the throwout cam for stopping the feed.

50 Fig. 4 is a top view of my attachment showing the guide rollers and feed rollers.

Fig. 5 is a detail of the throwout lever mechanism.

Fig. 6 is a cross section of the pawl and ratchet feed mechanism shown in Fig. 7.

Fig. 7 is a diagrammatic view showing a 55 modified form of the throwout cam.

Fig. 8 is a sectional view of the burners at the back of the matrix.

The standard parts of a small printing press will at once be recognized in Fig. 1. 60 The fixed frame is shown at 1 on which is pivoted the usual platen 2. The large fly-wheel pulley 3 is journaled on shaft 4 and may be driven from a motor 5 by a belt 6. Pinion 7 on said shaft 4 drives gear 8 on 65 which is pivoted at 9 a crank 10, which oscillates the bed 11 of the press. Said crank is connected, however, to the oscillating member 12 pivoted on the bed, which usually serves to ink the type, but from which the inking 70 rollers have been removed. Platen 2 is connected to member 12 by link 13 to give the former an oscillatory movement. The usual throwout lever is shown at 14. The bed plate is adapted to hold the usual type 75 matrix 15. All of the above described parts are well known in the art of presses.

To convert the press into a leaf applying or stamping machine, I replace the usual inking pad on top of the bed by special 80 mechanism 16 comprising a plurality of rollers 17 and 18 journaled in parallel side bars 19. The upper rollers 17 receive the white or plain paper 40 on which the lettering is stamped while the lower rollers 18 receive the gold or other leaf paper 41. Each strip is fed from a roll 40', 41' pivoted on the base of the bed. One of the upper rollers 17' is shown as mounted on pivoted 85 bracket 20, which may be adjusted to bring the knife in the proper relationship to the lettering. Automatic feeding of each strip of paper is provided by means of the feed rollers 21 and 22 which grip the respective strips between the surfaces thereof and the smaller rollers 17'' and 18''. 90

95 Preferably I provide an independent intermittent feed for each feed roller. On the shaft 23 of roller 22 is secured ratchet wheel 24, while loosely mounted on said shaft is a second ratchet wheel 25 to the face of which is secured gear 26. Meshing with said gear is a pinion 27 on the shaft 28 of upper feed roll 21. Both pawls 29 and 30 for the two ratchets 24 and 25 are pivoted on an arm 31 loosely journaled on shaft 23 and oscillated by link 32 from member 12 (see Fig. 1), so both pawls are oscillated together. A cam 100

105

surface (34 and 35) is pivoted adjacent each ratchet and under each pawl. Each cam is adjustable with respect to its ratchet as by set screws 36 and 37, so as to vary the effective stroke of each pawl as desired. This is accomplished by having a lug 38 on each pawl which raises the pawl above the ratchet teeth as long as said lug engages the top of the cam. Spring pressed rollers 39 may be provided to hold normally the ratchets against turning.

I may also provide a knife mechanism to sever the printed strip into given lengths. As shown, this mechanism comprises a knife 45 pivoted at 46 and linked at its outer end to a link 47. Said link in turn is pivoted at its other end to the lever 48 and intermediate its ends to a second lever 50. Both of said levers are pivoted to an extension 51 on the frame, thereby forming a parallel linkage. Lever 50 has pivoted to its outer end a rod 52 which is clamped in a bracket 53 pivoted to member 12 at 54. By this means it will be seen the knife is given a cutting stroke for every oscillation of the member 12. The length of each strip severed is controlled by varying the rate of feed.

The used gold-leaf paper may, if desired, be rerolled as by providing a roller 55 at the back of the machine (Fig. 4), which may be turned from the shaft 23 as by pulley 56, belt 57 and pulley 58 on the shaft 59 of the roller 55. If desired also, the printed paper may be rerolled instead of cutting the same into strips or labels. If this is desired, the same or a similar roller 55 may be employed for this purpose.

Preferably I provide means for quickly stopping the feed and thus interrupting the printing operation without stopping the entire machine. For this purpose I make use of the regular throwout handle 14 of the press as shown in Fig. 5, which shows a view looking in the reverse direction from Fig. 1. The handle 14 is connected through links 58', 59', and 60 and lever 61 to an arm 62 on a cam member 63, which is mounted on the hub 80 of disc 68, said disc in turn being mounted on shaft 23. Said member 63 is provided on the face thereof with cam surfaces or lugs 64 which take in apertures 65 in an adjacent member 66 on a shaft 23. When member 63 is rotated with respect to member 66, the lugs 64 ride up on the edges of the apertures 65 and push the member 63 to the right in Fig. 3. This forces cam 67 to the right, said cam being the back of disc 68 which supports member 63. This raises the rod 70 (Fig. 2 and 3) which in turn lifts the lever 71, having a cross bar 81 attached thereto, thereby raising both pawls clear of the ratchet teeth so that the feed is stopped. Member 63 is normally pressed to the left by means of spring-pressed plungers 72 and 73.

In order that the gold leaf may be transferred with the best results, I prefer to heat the type and for this purpose may provide gas-burners 74 at the back of the bed or matrix.

An alternative means for raising the pawls is shown diagrammatically in Fig. 7. In this view the cam 75 is turned directly by the rod 60 and engages the roller 76 on link 70. As before, link 70 is pinned adjacent one end to a link 70', and at the other end to the operating lever 71. It will readily be seen when the cam 75 is turned clockwise in Fig. 7 that the lever 71 will be raised to lift the pawls as in the other form of the invention.

From the foregoing, the operation of my invention will be readily understood. The movements of the press proper are exactly the same as when used as a printing press. Two sheets of paper are, according to my invention, fed across the face of the type, one being the paper or other article to be stamped with the gold leaf, and the other the gold leaf paper. As the two strips are fed across the face of the type, the bed of the press and the platen are brought together in the usual manner and the gold transferred to the paper where the type is pressed against the back of the gold paper. Both strips are fed together automatically by the mechanism described, the feed of each being varied at will by means of the adjustable cams 34 and 35. The printed strip may be severed after each print by means of the knife 45 as described while the whole printing operation can be instantly arrested by throwing the handle 14 thereby stopping the feed.

In accordance with the provisions of the patent statutes, I have herein described the principle of operation of my invention, together with the apparatus, which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having herein described my invention what I claim and desire to secure by Letters Patent is:

1. In a metallic leaf lettering attachment for job printing presses, the combination with the movable member which normally actuates the inking rollers of the press, of means for feeding a strip of the leaf, and means for feeding a strip of paper or other material, both of said means being actuated by the movements of said member.

2. In a metallic leaf lettering attachment for job printing presses, the combination with an oscillatory portion of the press, of means for feeding a strip of the leaf and means for feeding a strip of paper or other material, actuated by the oscillations of said portion, and means for varying the feed of each strip. 65
3. In a leaf lettering attachment for job printing presses, the combination with an oscillatory portion of the press, of means for feeding a strip of the leaf, means for feeding a strip of paper or other material, means for cutting said first-named strip into sections, and means for actuating said three first means from the oscillations of said portion. 70
4. In a leaf applying attachment for presses, the combination with the bed frame of the press and the movable member mounted thereon which normally actuates the inking rollers, of an attachment adapted to be placed on the top of said frame comprising a plurality of guide rollers, a feed roller and means for actuating said feed roller comprising a pawl and ratchet mechanism operated by the movements of said member. 75
5. In a leaf applying attachment for presses, the combination with the bed frame of the press and the oscillatory inking member thereof, of a frame adapted to be placed on the top of said frame comprising a plurality of guide rollers, a feed roller, means for actuating said feed roller comprising a pawl and ratchet mechanism operated by the oscillation of said inking member, a cutting means on said frame and means for also operating the same by the oscillation of said inking member. 80
6. In a leaf applying attachment for presses the combination with the bed frame of the press, of an attachment adapted to be placed on the top of said frame comprising a plurality of guide rollers, a feed roller for the sheet of material being stamped, a feed roller for the metallic leaf, a common means for actuating each feed roller, and means for varying the relative rate of feed. 85
7. In a leaf applying attachment for presses, the combination with the bed frame of the press and the oscillatory inking member mounted thereon of an attachment adapted to be placed on the top of said frame comprising a plurality of guide rollers a feed roller for the sheet of material being stamped, a feed roller for the metallic leaf, means for actuating each of said feed rollers by the oscillation of said inking member, and means for varying the rate of feed of at least one of said feed rollers. 90
8. In a metallic leaf lettering attachment for job presses, the combination with the oscillatory portion of the press, of means for feeding a strip of the leaf, means for feeding a strip of paper or other material, means for cutting said first named strips into sections, and means for actuating said three first named means from the oscillations of said member. 95
9. In a metallic leaf lettering attachment for job presses, the combination with the oscillatory member which normally actuates the inking rollers of the press, of means for feeding a strip of paper or other material, means for feeding a strip of the leaf, both of said means being actuated by the oscillations of said member, and reroll means for at least one of the strips also actuated by the oscillations of said member. 100
10. In a metallic leaf applying machine, the combination with the reciprocatory stamping means, of means for intermittently feeding the sheet of material being stamped, means for simultaneously feeding a sheet of metallic leaf paper in juxtaposition to the first-named sheet, means for varying at will the feed of either sheet, and a common means for throwing out both feeds. 105
11. In a metallic leaf applying machine, the combination with the reciprocatory stamping means, of feeding means for the sheet of metallic leaf and the work sheet comprising a pair of pawl and ratchet mechanisms, a common means for reciprocating the pawls, and a cam member adjustably mounted adjacent each pawl and adapted to prevent the adjacent pawl from engaging its ratchet throughout a greater or less portion of its stroke, whereby the rate of feed of either sheet may be varied 110 at will. 110
12. In a metallic leaf applying machine, the combination with the reciprocatory stamping means, of feeding means for the sheet of metallic leaf and the work sheet comprising a pair of pawl and ratchet mechanisms, a common means for reciprocating the pawls, a cam member adjustably mounted adjacent each pawl and adapted to prevent the adjacent pawl from engaging its ratchet throughout a greater or less portion of its stroke, whereby the rate of feed of either sheet may be varied at will, and a common means for throwing out the feed of both pawls. 115
13. In a leaf lettering attachment for job presses, the combination with the oscillatory member which normally actuates the inking rollers, of means for feeding a strip of the leaf, means for feeding a strip of paper or other material, means for cutting said first named strips into sections, and means for actuating said three first named means from the oscillations of said member. 120

In testimony whereof I have affixed my signature.

JAMES C. COON.
